John W. Rhodes, Inventor.
By Bond Adams & Shepard, Atty's.

UNITED STATES PATENT OFFICE.

JOHN W. RHODES, OF HAVANA, ILLINOIS.

METALLIC FLASK-HOLDER.

SPECIFICATION forming part of Letters Patent No. 498,403, dated May 30, 1893.

Application filed April 4, 1892. Serial No. 427,762. (No model.)

To all whom it may concern:

Be it known that I, JOHN W. RHODES, a citizen of the United States, residing at Havana, in the county of Mason and State of Illinois, 5 have invented certain new and useful Improvements in Casting Apparatus, of which the following is a specification, reference being had to the accompanying drawings, in which—

10 Figure 1 is section upon line 11 of Fig. 2, and Fig. 2 is a top or plan view.

My invention relates to improvements in holders of metallic flasks, and particularly to an improvement in the apparatus for casting 15 metallic objects shown and described in Letters Patent of the United States, No. 420,664, dated and issued February 4, 1890, to the Havana Press Drill Company, assignee of Harvey J. Phelps.

20 Heretofore it has been customary to place the sprue upon the top of the cope of the flask. By this arrangement the gate of the metal left when the flask was removed from the casting was left upon the end of the hub 25 of the wheel, which rendered it difficult to break off or otherwise remove the gate without breaking the hub; it often happened too that in the old way of pouring the metal against the end of the core the metal would 30 blow, thereby causing imperfect wheels. To obviate this I have designed the herein described mechanism, by means of which the sprue may be located upon the side of the flask instead of at the end or on the top of the 35 cope, thereby forming a shorter and smaller gate, which can be more readily broken off or otherwise removed from the hub of the wheel. I attain this object by means of the mechanism hereinafter described and illustrated in 40 the drawings. That which I regard as new will be pointed out in the claims.

In the drawings—1 indicates a metallic flask consisting of a drag 2 and cope 3.

4 indicates a frame for the drag which is 45 provided with four radially extending arms 5.

6 indicates an upright extending upward from the top surface of the frame 4.

7 indicates a lever pivoted at one end to the upright 6.

50 8 indicates an upright extending upward from the top surface of the frame 4, and upon the opposite side of the flask from that in

which the upright 6 is located. The upper end of the upright 8 adapted to pass through an opening in the lever 7, and is perforated 55 to receive a pin 9.

10 indicates a pivot pin which is bolted or otherwise secured to the under surface of the frame 4 a little to one side of the central line thereof, and has its two ends projecting a short 60 distance beyond each side of the frame 4.

11 indicates uprights which are secured to a suitable base, not shown in the drawings. The uprights 11 are provided with upward and outward extending arms 12 and 13; the 65 arm 12 is of such a height that its top may come upon a level with the top of the upright 11; the arm 13 is shorter, and is of such length as to support the flask frame 4 when inclined to the position indicated by the dotted lines 70 in Fig. 1. The upright 11 is provided at its top with a recess 14 adapted to receive the ends of the pivot pins 10, and these pins are so located on the frame 4 that the latter is held by gravity in the position indicated by 75 full lines Fig. 1 or in the position indicated by dotted lines Fig. 1.

15 indicates a sprue located upon the side of the flask 1.

The operation of my device is as follows: 80 The frame of the flask is placed, as is shown in the full lines in Fig. 1, with the drag of the flask, in position when the wheel is placed in position, as described in Letters Patent, No. 420,664, and the cope of the flask is placed 85 upon the drag; the lever 7 is brought down over the top of the cope to the drag and secured in place by the pin 9 in the top of the upright 8. The frame is then tilted into the position shown by the dotted lines in Fig. 1, 90 in which position the sprue 15 will be upon the upper side of the flask and the metal can be poured into the sprue.

I have not shown or described herein the form of the flask or devices for holding the 95 core in position, neither have I described the device for securing the wheel to the frame for the purpose of casting the hub upon it, as the form of this is not in any way essential to this invention.

I do not confine myself to the precise form of upright 8 and pin 9 hereinabove described as it is obvious that other means could be provided for locking the lever 7 in place

for the purpose of holding the cope upon the drag.

That which I claim as my invention, and desire to secure by Letters Patent, is—

- 5 1. The combination with a flask 1 consisting of a drag 2 and a cope 3, of a frame 4 for supporting said flask, pivots 10 secured to said frame, uprights 11 adapted to receive the pivots so as to support the frame and provided
10 with two arms 12 and 13 projecting upward and outward in opposite directions from said uprights, one of said arms having its upper end arranged to support the frame in a horizontal position and the other to support the
15 frame in an inclined position, and means for holding the cope upon the drag, substantially as described.
2. The combination with a flask 1 consisting of a drag 2 and a cope 3, of a flask-supporting-frame 4 having pivots 10 secured thereto at one side of the center thereof, uprights 11 supporting the pivots of the frame and provided with two arms 12 and 13 projecting upward and outward in opposite directions from said uprights, one of said arms
25

having its upper end arranged to support the frame in a horizontal position and the other to support it in an inclined position, and means for holding the cope upon the drag, substantially as described.

3. The combination with a flask 1 consisting of a drag 2 and a cope 3, of a frame 4 for supporting said flask, pivots 10 secured to said frame, uprights 11 adapted to receive said pivots so as to support said frame, and provided with two upward and outward extending arms, 12 and 13, said arm 12 being adapted to support said frame in a horizontal position, and said arm 13 being adapted to support said frame in an inclined position, a lever 7 pivoted to the upper surface of said frame and adapted to hold said cope upon said drag, and means for locking said lever down upon said cope, substantially as described.

JOHN W. RHODES.
